(57) **CLAIM**

The ornamental design for a water shoe, as shown and described.

DESCRIPTION

FIG. 1 is a perspective view of a water shoe showing my new design;

FIG. 2 is another perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged view of the encircled portion labeled “9” in FIG. 1; and,

FIG. 10 is an enlarged view of the encircled portion labeled “10” in FIG. 2.

The equal-length broken lines depict portions of the water shoe that form no part of the claimed design.

The dash-dot-dash broken lines in FIGS. 1, 2, 9, and 10 are used to annotate an area of enlargement and form no part of the claimed design.
